UNITED STATES PATENT OFFICE.

JOHN B. WICKERSHAM, OF NEW YORK, N. Y.

FOLDING BEDSTEAD.

Specification of Letters Patent No. 17,460, dated June 2, 1857.

To all whom it may concern:

Be it known that I, JOHN B. WICKERSHAM, of the city, county, and State of New York, have invented, made, and applied to 5 use a new and useful Improvement in the Joints of Portable or Fold-Up Iron Bedsteads; and I do hereby declare that the following is a full, clear, and exact description of the construction and operation of the 10 same, reference being had to the annexed drawing, making part of this specification, wherein—

Figure 1, is a side elevation of an iron bedstead with my improvement, as opened 15 ready for use. Fig. 2, is an elevation of the same in its closed position, or folded up. Fig. 3, is an elevation of the inner side of one of the legs, and Fig. 4, is an edge view of the same.

20 Similar marks of reference denote the same parts.

Metallic bedsteads have long since been constructed in such a manner as to fold up; my invention therefore simply applies to 25 the joint itself, made use of in such bedsteads; and to show the distinction between my construction of joint and others I will first briefly describe the joints that have heretofore been employed. A short project- 30 ing bar or plate with two holes has heretofore been riveted on to each post of the bedstead, and each of the horizontal rails has been provided with two similar holes. Through the end holes a tie rod has been 35 passed, that became a center pin on which to fold up the bedstead, and then by the insertion of a pin through the respective pairs of coinciding holes the bedstead has been retained in an unfolded position, but this is 40 both difficult and unreliable; difficult on account of getting the holes for the pins to match, particularly when the bedstead gets bent or twisted as is often the case; unreliable, because all the strain comes on the 45 pins, and the bedstead falls down unless the pins are inserted. The pins have also been thrown in by springs, but the same objections apply to this method, and the cost is considerably enhanced.

50 The nature of my said invention consists in forming a recess or shoulder in the corner post receiving the horizontal rails when the bedstead is opened, in combination with a pin inserted over the rail, whereby the 55 weight and strain are taken on said shoulder of the post and the joint pin and movable

pin relieved of the same, and no difficulty arises in making the holes coincide, and the bedstead will stand, even without inserting the movable pins, thereby greatly facilitat- 60 ing the insertion or withdrawal of the pins for folding or unfolding the bedstead.

The bedstead is to be of any suitable width or length and the parts may be formed more or less ornamental. 65

A, A, are the metallic posts connected by rods 1, and 2, to form either the head or foot board.

B, B, are the side rails jointed at 3 and 4 to the short legs C, in the usual manner, so 70 that when unfolded the square points of the shoulders abut against said leg and retain the same vertically.

α is a shoulder formed on, or by a recess in the post A, onto which the underside of the 75 rails B, at their ends, rest, and the rods 2, pass through holes in the ends of the rails B, in such a manner as to allow the bedstead to assume a folded or unfolded position, by the rails B being turned on said rods as 80 shown; and for convenience of transportation the rails B, at one end may be notched above the hole so as to allow the same to be unhooked.

5, 5, are movable pins inserted through 85 corresponding holes above the rails B when the bedstead is in an unfolded position, to confine said rails to the shoulder α , and the upper part of the rails B, may be slightly notched to pass the said pin, or not provided the casting of the post be sufficiently 90 wide to allow room for the pin entirely above said rail, which latter arrangement I prefer as preserving the entire strength of the rails B. 95

I do not claim a fold up bedstead, neither do I claim securing the side rails by the insertion of a pin through two holes, but

What I claim and desire to secure by Letters Patent is—

Securing the side rails in place when the bedstead is in an unfolded position by the combined operation of the shoulder α , and pin 5 inserted above the rail, substantially as and for the purposes specified. 100

In witness whereof I have hereunto set my signature this eleventh day of April 1857.

JOHN B. WICKERSHAM.
